UNITED STATES PATENT OFFICE.

ALFRED ROGERS, OF MILTON, MASSACHUSETTS.

SPOUT AND HOUSING.

Application filed March 5, 1921. Serial No. 450,076.

To all whom it may concern:

Be it known that I, ALFRED ROGERS, a citizen of the United States, residing at Milton, in the county of Norfolk and State of Massachusetts, have invented new and useful Improvements in Spouts and Housings, of which the following is a specification.

This invention has relation to plumbing or bath-room fittings, and has for its object to provide a water-delivery spout and a noncorrodible detachable housing therefor.

On the accompanying drawing,

Figure 1 represents in vertical section, on the line 1—1, Figure 2, a spout and housing embodying my invention.

Figure 2 represents the same in front view, with the hose coupling in place.

Figure 3 represents a section on the line

3—3, Figure 1, with the washers removed.

Figure 4 shows the spout in end rear elevation.

The fitting, which I have selected as best exemplifying my invention is intended for use on bath tubs, sinks or other fixtures wherein there is a vertical wall through which a water supply pipe may be projected. Hence at 10 I have shown a wall which may be a portion of a bath tub, sink, hopper, or a slab located at some place where it is desirable to deliver water. This wall has an aperture 11, through which the threaded end of a supply pipe 12 may be projected. A spout of brass or other suitable metal is shown at 13, which may be in the form of an elbow and which is internally threaded at its inner side to receive the end of the supply pipe. Its inner end is also preferably provided with a circular peripheral flange 14, and in front thereof with two radially-projecting locking lugs 15. At its outer end, the spout is internally threaded to receive a hose coupling 16 such as ordinarily supplied with bath tub spouts or faucets. This coupling has a knurled flange 161 at some little distance from its inner end, so that it is spaced from the outer or delivery end of the spout.

For the spout which I have thus described, I employ a non-corrodible housing 17 which may be made of vitreous china, celluloid, enameled iron or other material which is not affected by air and moisture. This housing may be made in a variety of forms so as to present an ornamental appearance while serving the utilitarian function of enclosing and concealing the spout. For ex-

ample, in the particular embodiment of the invention as illustrated, the housing is bulbous, or more or less spherical. It has on one side a circular dished flange 18, the end of which may be brought into plane engagement with the front face of the upright wall 10; and it has also an internal flange 19, which is less in diameter than the distance between the ends of the locking lugs 15. This flange 19 provides an aperture 20 large enough to receive the flange 14 at the inner end of the spout, and it has two recesses 21, 21, through which the locking lugs 15 may be projected. The housing has also a circular aperture at 22, encircled by an annular flange or apron 23, the axis of which is perpendicular to the axis of the aperture 20.

The housing is clamped to the wall 10 by a metal nut 24, screwed on the pipe 12, and of a diameter greater than the aperture 11 in the wall 10. To prevent injury to the parts in clamping the housing in place, I employ on the front face of wall 10 a thick resilient washer 25 of rubber or other compressible cushioning material and a metal washer 26, both of which are greater in diameter than the aperture 11, and which are located and concealed within the flange 18 of the housing.

The parts are assembled as follows:—On the pipe 12 is placed the nut 24, and the end of the pipe projected into the aperture 11 in the wall 10. The spout is inserted through the aperture 20 into the housing, front end foremost, with the lugs 15 registering with the recesses 21, until the lugs have passed the flange 19, whereupon the housing and the spout are rotated relatively to each other through an angle of 90° until said lugs 15 engage stops 27 (see Figure 3) formed interiorly on the housing, which brings the delivery end of the spout into registration with the aperture 22. Now the hose coupling is inserted through aperture 22 and screwed into the front or delivery end of the spout. The washer 26 and the rubber washer 25 are next placed on the protruding end of pipe 12, and then the spout 13 is screwed on the end of the pipe. The hose coupling 16, which projects through the aperture 22 of the housing, causes the housing to rotate with the spout, as the spout is screwed on the end of the pipe. After the spout has been screwed far enough to cause the washer 25 to be some-

what compressed, and to bring the delivery end of the spout into proper position as shown in Figure 1, the nut 24 is now rotated to clamp the parts more tightly together against the wall 10. After these acts have been performed, the hose coupling may be removed, and the spout is entirely concealed within the housing.

Of course I do not need a hose coupling, as I may insert a stick of wood or any other element through the flange 23 into the end of the spout to prevent the spout and housing from relative rotation in attaching the parts to and removing them from the pipe 12. The rubber washer 25 should be sufficiently thick and compressible to enable one to bring the end of the flange 18 against or close to the front face of the wall 10, without danger of breaking the flange 19, in case the housing is made of china or other relatively brittle or frangible material.

It will be observed that the housing preferably forms no part of the water conduit, so that, if it is broken, it does not interfere with the delivery of the water from the spout, although the flange 23 below the delivery end of the spout may, if desired, constitute an extension of the spout.

I have not shown the usual valves by which the flow of water through pipe 12 and spout or elbow 13 is controlled, as these, per se, form no part of the present invention.

Having thus explained the nature of my said invention and described a way of making and using the same, although without attempting to set forth all of the forms in which it may be made or all of the modes of its use, what I claim is:—

1. A fitting for bath tubs and the like, comprising an elbow-shaped spout, and a housing of noncorrodible material therefor having apertures registering with the inner and outer end of said spout and concealing said spout, said spout and housing having interlocking members which permit the detachment of one from the other.

2. In combination, a spout, a non-corrodible housing therefor, said spout being threaded to receive a pipe, locking lugs at one end of said spout, and internal members carried by said housing interlocking with said lugs.

3. In combination with a wall having a hole therethrough, of a spout, a non-corrodible housing therefor, said spout being threaded to receive a pipe passing through said hole, locking lugs at one end of said spout, internal members in said housing interlocking with said lugs, and means for clamping together said housing, spout and wall.

4. A fitting for bath tubs and the like having a wall, comprising a housing having an aperture encircled by a flange to abut said

wall and a second aperture at an angle thereto, an elbow-shaped spout enclosed by said housing with its inner and outer ends registering with said apertures respectively and having means for clamping said flange 70 against said wall.

5. The combination with a threaded pipe, and an apertured wall, of a spout screwed on the pipe, a housing enclosing said spout and having apertures registering with the inlet and outlet ends of the spout, and means for clamping said pipe, wall, housing and spout against relative dislocation.

6. A spout housing consisting of a bulbous casing of noncorrodible material having apertures whose axes are intersecting, said casing having annular flanges encircling both of said apertures.

7. A spout housing consisting of a bulbous casing of noncorrodible material having apertures whose axes are intersecting, said casing having an internal flange with notches or recesses therein and an external dished flange, encircling one of said apertures.

8. A fitting for bath tubs or the like, comprising a spout having its inlet end threaded, and also having radially projecting lugs at its inlet end, a bulbous housing of non-corrodible material having apertures registering with the inlet and outlet ends of said spout and having internal members for engagement with said lugs, and a dished flange for engagement with the face of a wall of a fixture, and a compressible washer concealed 100 in said dished flange.

9. A fitting for bath tubs or the like, comprising a spout having its inlet end threaded, and also having radially projecting lugs at its inlet end, a bulbous housing of non-corrodible material having apertures registering with the inlet and outlet ends of said spout and having internal members for engagement with said lugs, a dished flange for engagement with the face of a wall of a fixture, a compressible washer concealed in said dished flange, a pipe threaded into the inlet end of the spout, and a nut on said pipe for engagement with the other face of such wall.

10. In combination with a wall having an opening therethrough and a pipe extending through said opening, of an elbow-shaped spout fixed at one end to said pipe, a casing surrounding said spout and having a pair of angularly disposed openings corresponding in position to the ends of said spout, and means carried at one end of said spout for engaging said casing about the margin of one of said pair of openings for retaining said casing in position against said wall.

11. In combination with a wall having an opening therethrough and a pipe extending through said opening, of an elbow-shaped spout engaging at its inner end the end of

- said pipe, a casing enclosing said spout and having a pair of openings therethrough, one of said openings being provided with a marginal flange formed to receive a washer 5 to effect a close joint with said wall surrounding said wall opening and the other of said casing openings being in substantial alinement with the outer portion of said spout, and means carried by said spout 10 gaging and retaining said casing in position against said wall.
12. In combination with a wall having an opening therethrough and a pipe extending through said opening, of an elbow-shaped 15 spout engaging at its inner end the end of said pipe, a casing enclosing said spout and having a pair of openings therethrough, one of said openings being provided with a marginal flange formed to receive a washer to 20 effect a close joint with said wall surrounding said wall opening and the other of said casing openings being in substantial alinement with the outer portion of said spout,
- and means carried by said spout, engaging said casing about the margin of one of said 25 pair of openings for retaining said casing in position against said wall.
13. In combination with a wall having an opening therethrough and a pipe extending through said opening, of an elbow-shaped 30 spout engaging at its inner end the end of said pipe, a non-corrodible casing enclosing said spout and having a pair of openings, the inner of said openings being provided with a marginal flange formed to receive a 35 washer to effect a close joint with said wall surrounding said wall opening, and the outer of said openings being in substantial alinement with the outer end of said spout, and means carried by said spout engaging 40 said casing about the margin of its inner opening for retaining said casing in position against said wall.

In testimony whereof I have affixed my signature.

ALFRED ROGERS.
